UNITED STATES PATENT OFFICE.

JEAN PIERRE SERVE, OF GIVORS, FRANCE.

TUBULAR BOILER.

SPECIFICATION forming part of Letters Patent No. 398,003, dated February 19, 1889.

Application filed December 4, 1888. Serial No. 292,610. (No model.)

To all whom it may concern:

Be it known that I, JEAN PIERRE SERVE, a citizen of the Republic of France, and a resident of Givors, in the said Republic, have invented certain new and useful Improvements in Tubular Boilers, of which the following is a specification.

The chief object of this invention is to neutralize in tubular boilers the disadvantageous effects due to the expansion of the tubes, particularly when the tubes and the boiler-shell are made of metals having a different coefficient of expansion. Thus, for instance, in the boilers of locomotives as usually constructed, the iron tube-plate of the smoke-box being much more rigid than the tube-plate of the fire-box, which is of copper, the difference of expansion between the body of the boiler and the cluster of tubes produces a considerable strain on the fire-box tube-plate, which rapidly disintegrates the metal and seriously damages the fire-box and the connections of the latter with the tubes.

My invention consists partly in relieving the tube-plate of the fire-box from the strain due to the lengthening of the tubes by allowing this strain to be taken up by a rigid resistance-plate or its equivalent placed behind the fire-box, and partly in allowing the tube-plate of the smoke-box to yield slightly to the action of the said elongation by means of the improved construction of the said plate or of its connections with the boiler.

Referring to the accompanying drawings, Figure 1 is a vertical longitudinal section of a locomotive-boiler containing my improvements. Fig. 2 is a similar vertical section showing a variation in the method of attaching the tube-plate to the end of the boiler nearer the smoke-box. Figs. 3, 4, and 5 are details hereinafter referred to.

As shown in Figs. 1 and 3, a plate, *b*, preferably of iron, with great resisting power, is placed behind the tube-plate *a* of the fire-box. Through this iron plate the tubes *c* freely pass. Each tube is provided with a projecting piece or collar, *d*, the edge of which meets the said plate *b*, which is itself solidly fixed in the boiler. The plate *b* may rest against the inner flange of the exterior wall of the fire-box or may be held in any other suitable

manner. It will be understood that under these conditions the plate *b* will offer an absolute resistance to the strains which would otherwise be exerted against the tube-plate *a* by the expansion of the tubes, and that this strain will now act in the opposite direction—namely, against the tube-plate *e* of the smoke-box. In order that plate *e* may yield to a certain extent under this strain, a certain amount of elasticity is imparted to the hinder part of the boiler, as follows:

In the arrangement shown in Fig. 1 the tube-plate *e* is somewhat larger in diameter than the body of the boiler *f*, and its outer edge is bent backward and downward to allow it to be fastened to the said boiler *f* and to produce the required elasticity in the plate. In the modification shown in Fig. 2 the tube-plate *e* is flat, and is connected with the body of the boiler *f* by means of an arched or corrugated flange, *g*, which is sufficiently elastic for the purpose above mentioned. If preferred, the tube-plate *e* may be attached to the boiler *f* by an internal arched flange instead of an external one. In any of these forms the slight outward displacement of the plate *e* is assisted by the steam-pressure in the boiler, which is produced at the same time as the heating of the tubes.

It will be understood that the interior pressure of the boiler will drive back the plate *e* to a degree depending chiefly on its diameter and on the resisting force of the attaching-flange; but these two elements may be so calculated as to render the displacement of the said plate proportional to the expansion of the tubes. Thus the amount of recoil of the tube-plate *e*, determined by the pressure of steam upon it, being equal to the corresponding expansion of the tubes, this expansion will not exert any great strain on the abutment-plate *b*.

In the arrangement shown in Fig. 1 the endwise movement of the tubes *c* in one direction is restrained by a resisting-plate, *b*, which is made in one piece. The upper edge of this plate does not project much above the upper edge of the tubes *c*, and so it allows a free passage for the water and steam; but it must be understood that for this plate *b* several parallel pieces may be substituted, the

said pieces being arranged in different vertical planes. These pieces may be of variable thickness to support a certain number of rows of tubes, the plates themselves being supported at the back by horizontal or vertical bars, rods, or suitable stays placed endwise, which stays will offer a considerable resistance and furnish a firm support to the partial abutment-plates. This method is particularly applicable when the system is applied to boilers of a large diameter. The projections *d* on the tubes may be formed either by a ring placed on the tube (see Fig. 4) or by means of a welded joint, leaving a projecting edge at the point of junction, as seen in Fig. 5.

It is evident that with this system the holes in the plate *e* must be of sufficient diameter to allow of the passage of the projections *d* of the tubes, and that the said tubes must be slightly enlarged at this end, as seen in Figs. 1 and 2 of the drawings.

I claim as my invention—

1. In a multitubular boiler, the combination, with the fire-box tube-plate and the boiler-tubes, of a rigid abutment plate or plates, *b*, pierced with holes for the passage of the tubes, and of a series of ferrules or projections, *d*, fixed to the said tubes and each 30 adapted to abut against the inner face of the said abutment plate or plates, whereby the

strain of the longitudinal expansion of the tubes on the fire-box tube-plate is transferred to the rigid abutment plate or plates, substantially as described.

35

2. In a multitubular boiler, a series of boiler-tubes furnished with rings or projections abutting against a fixed abutment plate or plates, *b*, at the fire-box end of the boiler, in combination with a smoke-box tube-plate of a different diameter from that of the body of the boiler and fixed to the said body by curved or arched flanges arranged around its inner or outer circumference and capable of permitting a certain amount of elasticity in the 45 said tube-plate, substantially as described.

40

3. In a multitubular boiler, the combination, with the fixed abutment plate or plates *b* and the tubes *c*, having projections abutting against the same at the fire-box end, of a boiler-shell provided at the smoke-box end with a slightly-elastic circumferential collar united with the smoke-box tube-plate, substantially as set forth.

45

In testimony whereof I have signed my name 50 to this specification in the presence of two subscribing witnesses.
